Jona Thimney

Selfs. Patent

The schedule referred to in the letter Patent and making part of the same, containing a description in the words of the said Jona Thimney himself of his machine for shelling Corn, Mincing Wheat and dressing Hay.

This machine for shelling corn, consists of a frame with four legs, so as to admit of a wheel made of plank, double. Or again, three feet diameter, from four to six inches thick, with the side filled with nails, without heads, : wide rows, one inch apart, or the wheel may be made of cast iron with the nails cast in with a place in the centre for grinding, by placing a plate on the frame with a small stopper placed over it. The frame to have a plank on the inside of the legs, filled with nails likewise.

This wheel when double ground must have the axle-tree to play back against a spring on the back side of the frame, so as to admit small or large ears to pass between the front of the frame or plank filled with nails, and the wheel, which shells the corn by rolling through.

Another principle of shelling corn on the same wheel, is by placing a plate of iron on one part of the frame near the front of the wheel for the ear to lay on, held against the wheel by a spring which is connected with a screw near the centre of the wheel which presses the ear against the wheel and forces the cob out sideways. This wheel may be turned by water or Horse, with crank beader or hand staff connected to the frame with a screw nearest the lower end, with a pulman round the crank, and fastened by a screw to the lower end of the hand staff. These purchase hand staff will answer for turning grind stones, or sawing by placing a saw on the crank of a fly wheel, which will answer for flay and wheat by placing swinging knives on it.

The knives may be fed wheat or other grain by a box similar to the cutting box, with which may be used a round block with pegs in it, which turn by coggs near the centre of the fly wheel.
